John Berent, Lockport, N. Y.

Application September 20, 1935, Serial No. 41,436

16 Claims. (Cl. 122—122)

This invention relates to a boiler and more particularly to a low pressure boiler for heating water or generating steam for warming buildings, although the same is also useful in other installations.

The objects of this invention are to provide a boiler of this character, which is constructed mainly of sheet steel or rolled boiler plate sections which are so organized that the same can 10 be manufactured at low cost, which enables water to be heated and steam generated quickly and economically, which has its interior readily accessible so that it can be easily cleaned and maintained in the most efficient condition, which 15 can be utilized as an incinerator for burning rubbish, and which is capable of being made in sections so the same can be conveniently transported, also installed in places difficult of access and also permits of varying the number of sections 20 in the boiler to suit the required capacity.

In the accompanying drawings:

Fig. 1 is a front elevation of a boiler embodying a satisfactory form of my invention.

Fig. 2 is a side elevation of the same.

Fig. 3 is a vertical longitudinal section, on an enlarged scale, taken on line 3—3, Fig. 1.

Fig. 4 is a vertical transverse section, on an enlarged scale, taken on line 4—4, Fig. 2.

Fig. 5 is a vertical longitudinal section of the 30 boiler, similar to Fig. 3, but showing the several sections of the same separate for convenience in explaining the invention.

Figs. 6 and 7 are vertical transverse sections, taken on the correspondingly numbered lines in 35 Fig. 5.

In the following description similar characters of reference indicate like parts in the several figures of the drawings.

In its general construction this boiler consists 40 of a base, a body resting on the base, and a cap or hood supported on the body.

The base which is mounted upon a foundation 45 of brick or any other suitable material is preferably constructed in the form of a box or enclosure which is equal in length and width to the size of the boiler and comprises two upright longitudinal side walls 11, 12 and two upright transverse walls 13, 14 connecting the corresponding front and rear ends of the side walls, 50 these members being preferably constructed of sheet steel or rolled boiler plate and resting at their lower edges on the foundation, as shown in Figs. 1—7. The space within this base, in the present case, is divided by a transverse upright 55 partition 15 of brick or other suitable material

into a front pit 16 and a rear pit 17 for the reception of ashes when heating the boiler with a hard fuel such as coal, wood or refuse, or these pits may contain parts of the burner mechanism when the boiler is heated by gas, oil, or mechanical stoker.

In the present construction it is assumed that hard fuel is used as the heating medium and for this purpose a comparatively long grate 18 is arranged at the upper edge of the base in the 10 front pit for supporting the fuel and for a like purpose a comparatively short grate 19 is arranged at the upper edge of the base in the rear pit, these grates being preferably mounted on brackets 20 projecting inwardly from the side 15 walls of the base.

Access to the front pit may be had through doors 21 in the front wall 13 and a door 22 in the adjacent part of one of its side walls and access to the rear pit may be had through a door 20 23 in one of the side walls of the base.

The body of the boiler comprises a plurality of sections which are mounted on the base in a longitudinal row and in the preferred construction form a front combustion chamber 24 above the 25 front grate 18 and a rear combustion chamber 25 above the rear grate 19. Although the number of sections in the body may vary to suit different sizes and conditions the organization shown in the drawings comprises four sections of 30 which two form part of the front combustion chamber, one forms part of the rear combustion chamber, and one forms part of both of these chambers. The foremost of these sections is provided with two upright longitudinal water legs 35 26, which are arranged on transversely opposite sides of the front part of the front combustion chamber and rest at their lower ends on the adjacent side brackets 20 of the base, an upright front water leg 27 arranged transversely on 40 the front side of the front combustion chamber and connected at its opposite vertical ends with the front ends of the respective side legs 26, a horizontal water chest 28 arranged transversely above the front combustion chamber and connected with the upper ends of the front and side legs 27, 26, and a plurality of upright heating tubes 29 arranged in the chest 28 and connected at their lower and upper ends with the upper and lower walls 30, 31 thereof so that the lower 50 ends of these tubes open into the upper part of the front combustion chamber. The above mentioned bottom and top walls of the chest 28, the front and rear walls 32, 33 thereof, the inner and outer walls 34, 35 of the side legs 26 and 55

the inner and outer walls 36, 37 of the front leg 27 are made of rolled boiler plate or sheet steel the adjacent edges of which are connected by welding, electric, acetylene or otherwise, so as to form an integral structure. The upright walls of this chest are connected by stays or rods 38, and the respective upright walls of the side and front legs 26, 27 are connected by stays or rods 39, 40, thereby holding these walls against displacement under the pressure to which they are subjected while in use.

In rear of the front body section is arranged an intermediate body section which has generally the form of an inverted U and comprises two upright longitudinal legs 41, arranged on transversely opposite sides of the front combustion chamber and resting at their lower ends on the adjacent side brackets 20 of the base and abutting at their front edges against the rear edges 20 of the legs 26, a horizontal water chest 42 arranged transversely over the front combustion chamber and bearing against the chest 29 and connecting the upper ends of the side legs 41 and a plurality of upright heating tubes 43 arranged in the chest 42 and connected at their lower and upper ends with the lower and upper walls 44, 45 of this chest so that the lower ends of these tubes open into the upper part of the front combustion chamber. Said lower and upper walls of the chest 42, the front and rear walls 46, 47 and the inner and outer walls 48, 49 are all made of rolled boiler plate or sheets of steel which are integrally connected by electric or gas welding and the walls of this chest are connected by horizontal stays or rods 50, and the walls of the legs 41 are connected by stays or rods 51 to prevent spreading of these walls under pressure.

40 In rear of the intermediate body section is a partition body section which forms part of the enclosure for the front and the rear combustion chambers. This partition body section comprises two upright longitudinal legs 52 arranged on transversely opposite sides of the front and rear combustion chambers and resting at their lower ends on the adjacent side brackets 20 of the base and fitting at their front ends against the rear ends of the legs 41, an upright partition leg 53 arranged transversely between the front and rear combustion chambers and resting at its lower end on the partition 15 between the front and rear pits, a horizontal water chest 54 extending transversely over the adjacent parts of the front and rear combustion chambers and bearing against the chest 42 and connecting the upper ends of the legs 52, 53, and a plurality of upright heating tubes 55, 56 arranged within the chest 54 and connected at their lower and upper ends with the bottom and top walls 51, 58 of this chest so that the lower ends of the tubes 55 open into the front combustion chamber and the lower ends of the tubes 56 open into the rear combustion chamber. The front and rear transverse walls 59, 60 of the chest 54 are connected by longitudinal stays or rods 61, its longitudinal side walls are connected by transverse stays 62 and the longitudinal walls of each of the legs 52 and the upright partition leg 53 are connected by stays or rods 63 to prevent these walls from yielding when subjected to internal pressure. The several walls of the partition body section are constructed of rolled boiler plate or sheets of steel which are welded together to form an integral structure.

The rearmost section of the body comprises two upright longitudinal water legs 64 which are constructed like the longitudinal legs of the front, intermediate and partition sections of the body and engage legs of the partition section while their lower ends rest on the adjacent brackets 20 of the base on opposite sides of the rear combustion chamber, a rear upright water leg 65 arranged transversely at the rear end of the rear combustion chamber and resting at its lower end on the transverse rear brackets 20 of the base and connected at its opposite vertical edges with the rear edges of the side legs 64, a horizontal water chest 66 arranged over the rear part of the rear combustion chamber and engaging the chest 54 and connecting the upper ends of the legs 64, 65, and a plurality of upright heating tubes 67 arranged in the chest 66 and connecting with the lower and upper walls 68, 69 of this chest so as to open into the rear combustion chamber. The front and rear upright walls 70, 71 of the chest 66 are connected by stays or rods 72, its longitudinal side walls are connected by transverse rods 73, the upright walls of each side leg 64 are connected by stays or rods 74 and the walls 75, 76 of the leg 65 are connected by stays or legs 77, thereby preventing these walls from spreading under pressure. The several walls of the rearmost body section are constructed of rolled boiler plate of sheets of steel which are connected by any well known method of welding in order to integrally connect the same. The lower end of each upright leg of the several body sections is closed by a plate of sheet steel or rolled boiler plate and may either consist of an extension on one wall of the respective leg and welded to the companion wall as shown at 82 in Figs. 3 and 4, or the same may be made separate and welded to both walls of a water leg, as shown at 83 in Fig. 3.

The cap or hood of the boiler is provided on its under side with a dome or passage 78 into which the upper ends of the heating tubes of the several body sections are arranged. This cap is preferably constructed in sections and in the present case consists of three sections arranged in a longitudinal row. The foremost section is arranged over the whole of the front body section and part of the intermediate body section arranged next to the front body section and comprises two upright longitudinal water legs 79 arranged on transversely opposite sides of the front part of the dome and resting on the front and intermediate body sections, an upright front water leg 80 arranged transversely on the front part of the foremost body section and connecting with the front ends of the side legs 79 of the respective cap section, and a horizontal water crown 81 connecting the upper edges of said side legs 79 and front leg 80. Each of the side legs has inner and outer walls 84, 85 which are connected at their lower edges by a plate 86, the front leg 80 has inner and outer walls 87, 88 which are connected at their opposite edges with the corresponding walls of the side legs 79 while the lower edges of the walls 87, 88 are connected by a plate 89, and the crown 81 has inner and outer walls 100, 101 which have their longitudinal edges connected respectively with the corresponding upper edges of the walls of the side legs 79 while their transverse front edges are connected respectively with the upper transverse edges of the inner and outer walls 87, 88 of the front leg 80 and the rear transverse edges of said crown walls are connected 75

with the upper and lower edges of an end plate 102 by welding or otherwise.

To prevent the walls of this cap section from spreading under pressure the same are preferably connected by suitable strengthening or reinforcing means, such, for example, as the stays, bolts or rods 103 connecting the walls of the front cap water leg 80, and the stays, bolts or rods 104 connecting the inner and outer walls of the water 10 crown 81.

The central section of the cap or hood is engaged at its front end with the rear end of the front cap section and partly over the intermediate body section and partly over the partition 15 body section and comprises two upright longitudinal water legs 105 arranged on transversely opposite sides of the central part of the dome 78, and a horizontal water crown 106 connecting the upper ends of the side legs 105. Each of the cap 20 legs 105 is provided with inner and outer walls 107, 108 which are connected at their horizontal lower edges by horizontal end plates 109. The crown of the central cap section has inner and outer walls 110, 111 which connect at their opposite longitudinal edges, respectively, with the corresponding upper edges of the inner and outer walls of the side legs 105. The corresponding front and rear edges of the walls of the water 25 legs and the water crown of the central cap section are connected, respectively, by end plates 112, 113, and these walls are braced relative to each other by stays, bolts or rods which connect them, as shown for example at 114 in Figs. 3, 4, 5 and 6.

The rear section of the cap or hood extends 30 over the entire rearmost body section and over part of the partition body section and engages its front end with the rear end of the central cap section, and comprises two upright longitudinal water legs 115 which rest at their lower ends on 35 the transversely opposite parts of the partition body and the rear body sections of the boiler, a rear upright water leg 116 mounted transversely on the rear part of the rear body section and connected at its opposite vertical ends with the rear 40 ends of the side legs 115 and a horizontal water crown 117 arranged over the rear part of the dome and connecting the upper ends of the side water legs 115 and the rear water leg 116. Each 45 of the side water legs 115 is provided with inner and outer walls 118, 119 which are connected at their lower edges by a horizontal end plate 120, the water leg 116 has inner and outer walls 121, 122 which are connected at their lower edges by a horizontal end plate 123, the crown 117 has 50 inner and outer walls 124, 125 which are connected with the upper edges of the walls of the side legs 115 and the transverse leg 116, and the front edges of the inner and outer walls of the side legs 115 and the crown 117 are connected by 55 vertical end plates 126. The inner and outer walls of the transverse leg 116 are connected by stays, bolts or rods 127 for sustaining the same against internal pressure and inner and outer walls of the side legs 115 and the crown 117 may 60 likewise be reinforced against displacement by stays, bolts or rods, such as those shown at 128 which connect the walls of the crown 117.

The walls and end plates of the several sections of the cap or hood are constructed of what is 65 commonly known as rolled boiler plate or sheet steel and the parts of each of these sections are united into one integral structure by welding them together in any well known manner either electrically or by gas.

70 The lower parts of the water spaces in the

several body sections are placed in communication with each other so that the water can flow freely from one to the other and distribute itself uniformly in the boiler. This is preferably accomplished by two manifolds or main conduits 129 arranged along the lowermost parts of the outer longitudinal sides of the several body sections and connected with each of said sections by transverse branch pipes 130. Fresh water is supplied to the boiler in any suitable manner but 10 preferably by connecting one or both of these manifolds with a source of water supply. A free circulation is also established between the several body sections and the cap sections, the preferred means for this purpose consisting of pairs of tubular necks or short pipes 131, 132 communicating respectively with the interior of the body sections and cap sections and projecting laterally from opposite longitudinal sides thereof adjacent to the horizontal joint between the body and cap 15 sections, and an elbow 133 connecting the outer ends of each pair of necks, as shown in Figs. 1, 2, 3, 6 and 7.

To permit of completely emptying the water 20 from the boiler and removing any mud which 25 may have settled in the lowermost part of the water legs of the body sections drain openings 134 are provided at suitable places in the lowermost part of the outer walls of these legs which 30 openings are normally closed by screw plugs 135.

When burning hard fuel, such as coal, coke or wood the same is introduced into the front combustion chamber and placed upon the front 35 grate 18 through a stoke hole or feed passage or opening 136 arranged in the lower part of the transverse water leg of the foremost body section and normally closed by a door 137. The smoke and waste gases resulting from the combustion of the fuel escapes from the rear combustion chamber and conducted to the chimney 40 or flue through a smoke pipe or outlet 138 arranged in the lower part of the transverse water leg of the rearmost body section.

As the fuel burns in the front combustion chamber the hot flames and gases pass upwardly 45 therefrom in contact with the inner walls of the respective body sections and through the heating tubes or flues of the front and intermediate body sections and those of the partition body sections which are arranged in front of the water partition leg 53, thence upwardly into the front part of the dome of the sectional cap, thence rearwardly in this dome to the rear part 50 of the same and in contact with the adjacent walls of the several body and cap sections, thence downwardly through the heating tubes or flues in the rearmost body section and those tubes or flues of the partition body sections which are arranged in rear of the partition water leg, thence downwardly in the rear combustion chamber 55 in contact with the several walls of the respective body chambers, and then escape through the smoke pipe or outlet passage 138 to the chimney. During this movement of the hot gases the same contact with maximum surface of the boiler and transmit heat to the water while the same is divided to very large extent into comparatively small masses so that all parts of the same are effectively reached by the heat, thereby enabling 60 heating the water to be heated rapidly and economically.

Due to the use of rolled boiler plate as the 65 walls of the body and cap sections of the boiler which material is very thin compared with cast iron, the heat of the hot gases is capable of passing 70

ing more rapidly and effectively through these walls and thus heat the water quicker and also maintain the water at a higher temperature by the consumption of a given amount of fuel.

5 The hot water or steam may be drawn off from the boiler in any desired manner, for instance by a manifold delivery pipe 139 arranged horizontally over the cap or hood and connected by branch pipes 140 with the several sections 10 of the same and also connected with a plurality of branch pipes 141 whereby the water or steam is conducted to the places where it is to be used.

Cleaning of the dome may be effected through clean-out passages 142, 143 arranged in the 15 transverse water legs of the front and rear cap sections and provided respectively with doors 144, 145 whereby the same may be opened or closed.

In addition to serving as a downtime for the 20 hot gases in the rear combustion chamber for obtaining the maximum heating effect of the same on the water before they escape from the boiler, this rear combustion chamber may be utilized as an incinerator for burning rubbish 25 and the like on the rear grate in this chamber and thus not only readily disposing of this rubbish but also utilizing any heating value contained therein. This rubbish may be introduced into the rear combustion chamber and deposited 30 on the rear grate 19 through a feed opening or passage 146 formed on the lower parts of adjacent side legs of the rearmost and partition body sections of the boiler on one side of the same above the rear grate which rubbish feed 35 passage is normally closed by a door 147.

In order to prevent the flames and hot gases resulting from the burning of the rubbish on the rear grate from passing directly out through the smoke pipe 138, an upright baffle or fire 40 bridge 148 is preferably arranged transversely over the rear grate between the feed opening 146 and the smoke outlet 138 and projecting upwardly from the rear grate and partly across the lower 45 side of the smoke pipe so that the hot gas and smoke rising from the fuel on the rear grate are compelled to first strike the inner walls of the respective body sections before their escape and thus utilize the burning rubbish advantageously by conserving the heat generating units 50 in the same.

Any ashes resulting from the burning of rubbish which fall through the rear grate into the rear ash pit may be removed from the latter upon opening the door 23 in the respective side 55 wall of the base.

In this construction the surface exposed to the heating medium is properly proportioned to the area of the grates and is ample for utilizing to the fullest extent the fuel which is consumed 60 thereby avoiding waste. The number of sections employed in the boiler may be varied to suit the required capacity of the same and also meet varying conditions of installation. Inasmuch as the area of the upper horizontal walls 65 of the water chests of the several body sections is comparatively small a minimum of horizontal shelf area is present on which soot and flying ashes might lodge, thereby maintaining the heating surface in the most effective condition and 70 also reducing any tendency to retard the draft through the boiler.

Due to the form of the several sections of the boiler the same can be made in any size or number and comparatively small and thus render it 75 possible to pass the same individually through

small door openings or like passages when this is necessary.

No unusual mechanical knowledge is required to erect this boiler as all the parts are of simple construction. As all the connections between 5 the several sections are on the exterior of the boiler the same are visible at all times for inspection and care.

By providing a front combustion chamber below the first set of heating tubes forming the 10 first or uptake pass for the heating medium and a secondary grate in the rear combustion below the second set of heating tubes forming the second or downtime pass, it is possible to not only 15 employ a main fuel for heating the water but also an auxiliary fuel such as rubbish to supplement the heating effect on the water and thereby enabling this boiler to be utilized as an incinerator without added expense.

As the products of combustion contact with 20 the upper surface of the dome in the cap sections a superheating effect is produced on the vapors or the water in the crowns of the cap sections, thus utilizing the fuel most advantageously.

Free circulation of the water is possible 25 through all parts of the boiler and no obstructions exist which interfere with the direct up and down travel of the water in the several sections.

By constructing all of the sections of the boiler 30 of rolled boiler plate the same are more flexible than conventional boilers made of cast iron and the same are also not subject to cracking and consequent leakage.

As a whole this boiler is exceedingly simple in 35 construction, its several parts can be manufactured and assembled at low cost and the same has no parts which are liable to get out of order thus reducing the cost of maintenance to a minimum.

40 I claim as my invention:

1. A boiler comprising a lower base, a body section resting on the base, and a cap resting on the body section, said body and cap sections being constructed as separate units which are independent and separable from one another, said base containing a pit, said body section having two vertical water legs on its opposite sides forming a combustion space between them, and a transverse chest connecting the upper ends of 50 said legs, said cap having a water space and containing a dome which opens downwardly, and a plurality of vertical heating tubes arranged in said chest and opening at their lower ends into said combustion space and at their upper ends 55 into said dome.

2. A boiler comprising a base, body sections arranged lengthwise one behind the other on said base and each having vertical water legs on its opposite sides and forming a combustion space 60 between the same, and a transverse chest connecting the upper ends of said legs, vertical heating tubes arranged in each of said chests and opening at their lower ends into the combustion space of the respective body section, and a cap 65 having a water space and provided on its underside with a dome communicating with the upper ends of the tubes of the respective body sections, said body sections and cap being constructed as separate units which are independent and separable from one another.

3. A boiler comprising a base, body sections arranged lengthwise one behind the other on said base and each having vertical water legs on its opposite sides and forming a combustion space 75

between the same, and a transverse chest connecting the upper ends of said legs, vertical heating tubes arranged in each of said chests and opening at their lower ends into the combustion space of the respective body section, and a cap having a water space and extending over adjacent body sections and resting thereon and provided on its underside with a dome which communicates with the upper ends of the tubes of the respective body sections, said body sections and cap being constructed as separate units which are independent and separable from one another.

4. A boiler comprising a lower base, a body section resting on the base, and a cap having a water space and resting on the body section, said base containing a pit, said body section having two vertical water legs on its opposite sides forming a combustion space between them, a transverse chest connecting the upper ends of said legs, said cap containing a dome which opens downwardly, a plurality of vertical heating tubes arranged in said chest and opening at their lower ends into said combustion space and at their upper ends into said dome, and a conduit connecting the interior of the body section with the interior of the cap, said body sections and cap being constructed as separate units which are independent and separable from each other.

5. A boiler comprising a base, body sections arranged lengthwise one behind the other on said base and each having vertical water legs on its opposite sides and forming a combustion space between the same, a transverse chest connecting the upper ends of said legs, and vertical heating tubes arranged in each of said chests and opening at their lower ends into the combustion space of the respective body section, a cap having a water space and extending over adjacent body sections and resting thereon and provided on its underside with a dome which communicates with the upper ends of the tubes of the respective body sections, and external conduits connecting the interior of each of said body sections with the interior of said cap, said body sections and cap being constructed as separate units which are independent and separable from each other.

6. A boiler comprising a base, body sections arranged lengthwise one behind the other on said base and each having vertical water legs on its opposite sides and forming a combustion space between the same, a transverse chest connecting the upper ends of said legs, and vertical heating tubes arranged in each of said chests and opening at their lower ends into the combustion space of the respective body section, a cap having a water space and provided on its underside with a dome communicating with the upper ends of the tubes of the respective body sections, and a conduit connecting the interior of adjacent body sections, said body sections and cap being constructed as separate units which are independent and separable from each other.

7. A boiler comprising a base, a front body section, a rearward body section arranged in rear of the front section and a cap arranged above said body sections and having a water space, said front body section having an upright front water leg extending transversely across the front section, two side upright water legs arranged on transversely opposite sides of this section and connected at their front ends with the opposite vertical ends of said front leg, a horizontal chest connecting the upper ends of said front and side legs and forming therewith a rearwardly opening

front part of a combustion chamber and vertical heating tubes arranged in said chest and opening at their lower ends into said front part of the combustion chamber, said rearward body section having an upright transverse partition leg, two side upright water legs arranged on transversely opposite sides of this section and connecting with the opposite vertical edges of said partition leg and a horizontal chest connecting the upper ends of said legs of said rearward body section, and a cap arranged above the front and rearward body sections and provided on its underside with a dome which communicates with the upper ends of said heating tubes, said body sections and cap being constructed as separate units which are independent and separable from each other.

8. A boiler comprising a base, a front body section, a rearward body section arranged in rear of the front section and a cap arranged above said body sections and having a water space, said front body section having an upright front water leg extending transversely across the front section, two side upright water legs arranged on transversely opposite sides of this section and connected at their front ends with the opposite vertical ends of said front leg, a horizontal chest connecting the upper ends of said front and side legs and forming therewith a rearwardly opening front part of a combustion chamber and vertical heating tubes arranged in said chest and opening at their lower ends into said front part of the combustion chamber, said rearward body section having an upright transverse partition leg, two side upright water legs arranged on transversely opposite sides of this section and connecting with the opposite vertical edges of said partition leg and a horizontal chest connecting the upper ends of said legs of said rearward body section and forming therewith a forwardly opening front part of a combustion chamber and vertical heating tubes arranged in said chest and opening at their lower ends into said front part of the combustion chamber, said rearward body section having an upright transverse partition leg, two side upright water legs arranged on transversely opposite sides of this section and connecting with the opposite vertical edges of said partition leg and a horizontal chest connecting the upper ends of said legs of said rearward body section and forming therewith a forwardly opening rear part of said combustion chamber, and a cap arranged above the front and rearward body sections and provided on its underside with a dome which communicates with the upper ends of said heating tubes, said body sections and cap being constructed as separate units which are independent and separable from each other.

9. A boiler comprising a base, a front body section, a rearward body section arranged in rear of the front section and a cap arranged above said body sections and having a water space, said front body section having an upright front water leg extending transversely across the front section, two side upright water legs arranged on transversely opposite sides of this section and connected at their front ends with the opposite vertical ends of said front leg, a horizontal chest connecting the upper ends of said front and side legs and forming therewith a rearwardly opening front part of a combustion chamber and vertical heating tubes arranged in said chest and opening at their lower ends into said front part of the combustion chamber, said rearward body section having an upright transverse partition leg, two side upright water legs arranged on transversely opposite sides of this section and connecting with the opposite vertical edges of said partition leg and a horizontal chest connecting the upper ends of said legs of said rearward body section and forming therewith a forwardly opening rear part of said combustion chamber, heating tubes arranged in the chest of said rearward body section and opening into the part of the combustion chamber therein, and a cap arranged above the front and rearward body sec-

tions and provided on its underside with a dome which communicates with the upper ends of said heating tubes, said body sections and cap being constructed as separate units which are independent and separable from each other.

10. A boiler comprising a base, a front body section, a rearward body section arranged in rear of the front section and a cap arranged above said body sections and having a water space, said front body section having an upright front water leg extending transversely across the front section, two side upright water legs arranged on transversely opposite sides of this section and connected at their front ends with the opposite vertical ends of said front leg, a horizontal chest connecting the upper ends of said front and side legs and forming therewith a rearwardly opening front part of a combustion chamber and vertical heating tubes arranged in said chest and opening at their lower ends into said front part of the combustion chamber, said rearward body section having an upright transverse partition leg, two side upright water legs arranged on transversely opposite sides of this section and connecting with the opposite vertical edges of said partition leg and a horizontal chest connecting the upper ends of said legs of said rearward body section, an intermediate body section arranged between said front body section and rearward body section and having two upright side water legs, a horizontal chest connecting the upper ends of the respective side legs and forming therewith an intermediate part of said combustion chamber, and a cap arranged above the front and rearward body sections and provided on its underside with a dome which communicates with the upper ends of said heating tubes, said body sections and cap being constructed as separate units which are independent and separable from each other.

11. A boiler comprising a base, a front body section, a rearward body section arranged in rear of the front section and a cap arranged above said body sections and having a water space, said front body section having an upright front water leg extending transversely across the front section, two side upright water legs arranged on transversely opposite sides of this section and connected at their front ends with the opposite vertical ends of said front leg, a horizontal chest connecting the upper ends of said front and side legs and forming therewith a rearwardly opening front part of a combustion chamber and vertical heating tubes arranged in said chest and opening at their lower ends into said front part of the combustion chamber, said rearward body section having an upright transverse partition leg, two side upright water legs arranged on transversely opposite sides of this section and connecting with the opposite vertical edges of said partition leg and a horizontal chest connecting the upper ends of said legs of said rearward body section, an intermediate body section arranged between said front body section and rearward body section and having two upright side water legs, a horizontal chest connecting the upper ends of the respective side legs and forming therewith an intermediate part of said combustion chamber, heating tubes arranged in the chest of said intermediate body section and opening at their lower ends into the part of the combustion chamber in the respective body section, and a cap arranged above the front and rearward body sections and provided on its underside with a dome which communicates with the

upper ends of said heating tubes, said body sections and cap being constructed as separate units which are independent and separable from each other.

12. A boiler having a front body section, a rear body section, an intermediate body section, and a cap arranged above said body sections and having a water space, each of said body sections having two upright water legs on transversely opposite sides thereof, an upright transverse wall connecting said legs and a horizontal chest connecting the upper ends of said legs and wall, the legs, walls and chests of said front and intermediate body sections forming between them a front combustion chamber and the legs, walls and chests of said intermediate and rear body sections forming between them a rear combustion chamber, upright heating tubes arranged in each of said chests and opening at their lower ends into the respective combustion chamber, and said cap being provided on its underside with a dome which communicates with the upper ends of the several heating tubes, said body sections and cap being constructed as separate units which are independent and separable from each other.

13. A boiler having a front body section, a rear body section, an intermediate body section, and a cap arranged above said body sections and having a water space, each of said body sections having two upright water legs on transversely opposite sides thereof, an upright transverse wall connecting said legs and a horizontal chest connecting the upper ends of said legs and wall, the legs, walls and chests of said front and intermediate body sections forming between them a front combustion chamber and the legs, walls and chests of said intermediate and rear body sections forming between them a rear combustion chamber, upright heating tubes arranged in each of said chests and opening at their lower ends into the respective combustion chamber, and said cap being provided on its underside with a dome which communicates with the upper ends of the several heating tubes, said body sections and cap being constructed as separate units which are independent and separable from each other, the transverse wall of said front body section being provided with an inlet to the front combustion chamber, and the transverse wall of said rear body section being provided with an outlet for the products of combustion.

14. A boiler having a front body section, a rear body section, an intermediate body section, and a cap arranged above said body sections and having a water space, each of said body sections having two upright water legs on transversely opposite sides thereof, an upright transverse wall connecting said legs and a horizontal chest connecting the upper ends of said legs and wall, the legs, walls and chests of said front and intermediate body sections forming between them a front combustion chamber and the legs, walls and chests of said intermediate and rear body sections forming between them a rear combustion chamber, upright heating tubes arranged in each of said chests and opening at their lower ends into the respective combustion chamber, and said cap being provided on its underside with a dome which communicates with the upper ends of the several heating tubes, said body sections and cap being constructed as separate units which are independent and separable from each other, the transverse wall of said front body section being provided with an inlet to the front combustion chamber, the transverse wall

of said rear body section being provided with an outlet for the products of combustion, and a water leg forming part of said rear combustion chamber and provided with an inlet for combustible material.

- 5 15. A boiler having a front body section, a rear body section, an intermediate body section, and a cap arranged above said body sections and having a water space, each of said body sections
10 having two upright water legs on transversely opposite sides thereof, an upright transverse wall connecting said legs and a horizontal chest connecting the upper ends of said legs and wall, the legs, walls and chests of said front and intermediate body sections forming between them a front combustion chamber and the legs, walls and chests of said intermediate and rear body sections forming between them a rear combustion chamber, upright heating tubes arranged
15 in each of said chests and opening at their lower ends into the respective combustion chamber, and said cap being provided on its underside with a dome which communicates with the upper ends of the several heating tubes, said body sections
20 and cap being constructed as separate units which are independent and separable from each other, the transverse wall of said front body section being provided with an inlet to the front combustion chamber, the transverse wall of said
25 rear body section being provided with an outlet for the products of combustion, a water leg forming part of said rear combustion chamber and provided with an inlet for combustible material, and a grate arranged in the lower part of said
30 rear combustion chamber.

16. A boiler having a front body section, a rear body section, an intermediate body section, and a cap arranged above said body sections and having a water space, each of said body sections having two upright water legs on transversely 5 opposite sides thereof, an upright transverse wall connecting said legs and a horizontal chest connecting the upper ends of said legs and wall, the legs, walls and chests of said front and intermediate body sections forming between them a front 10 combustion chamber and the legs, walls and chests of said intermediate and rear body sections forming between them a rear combustion chamber, upright heating tubes arranged in each of said chests and opening at their lower 15 ends into the respective combustion chamber, and said cap being provided on its underside with a dome which communicates with the upper ends of the several heating tubes, said body sections and cap being constructed as separate 20 units which are independent and separable from each other, the transverse wall of said front body section being provided with an inlet to the front combustion chamber, the transverse wall of said rear body section being provided with 25 an outlet for the products of combustion, a water leg forming part of said rear combustion chamber and provided with an inlet for combustible material, a grate arranged in the lower part of said rear combustion chamber, and a fire wall in 30 said rear combustion chamber above the rear part of said grate and between said inlet and outlet of said last mentioned chamber.

JOHN BERENT. 35
